United States Patent Office.

CASPAR FERSCH, OF NEW YORK, N. Y., ASSIGNOR TO HOFFMAN AND FERSCH.

Design No. 2,853, dated December 31, 1867.

DESIGN FOR A MOULDING FOR SHOW-CASES.

The Schedule referred to in these Letters Patent and making part of the same.

TO ALL WHOM IT MAY CONCERN:

Be it known that I, CASPAR FERSCH, of the city, county, and State of New York, have invented a new Design for the Moulding for Frames of Show-Cases; and I do hereby declare that the following is a full, clear, and exact description of the same, reference being had to the accompanying drawing making a portion of this specification.

This design relates to the exterior form of the framework employed to hold in place the glass panes or plates of show-cases, and the drawing shows a transverse section of one of the bars of which such framework is formed. At the inner side of such bar are formed the two angular rebates, *a*, which receive the edges of the glass panes or plates of the case. The top, *b*, of the bar is made flat, and the outer side, *c*, situated in a plane at right angles to the aforesaid top, is also flat. Between the contiguous edges of the just-mentioned top and outer side of the bar, is an inclined surface, *d*, situated at an angle of about forty-five degrees with reference to such top and outer side. The surface of the bar, between the back and lower edges respectively of the top and outer side thereof, and the edges of the adjacent rebates, *a*, are formed on the arc of a circle, as shown at *e*.

What I claim as my invention, and desire to secure by Letters Patent, is—

The within-described design for the mouldings for frames of show-cases, substantially as set forth and shown.

CASPAR FERSCH.
